(57) CLAIM

The ornamental design for a capacitive discharge ignition box, as shown and described.

DESCRIPTION

FIG. 1 is a top perspective view of a capacitive discharge ignition box showing my new design;
FIG. 2 is a front view thereof, a rear view being a mirror image of the front view;
FIG. 3 is a left side view thereof;
FIG. 4 is a right side view thereof;
FIG. 5 is a top view thereof;
FIG. 6 is a bottom view thereof, and,
FIG. 7 is a bottom perspective view thereof.
